UNITED STATES PATENT OFFICE

157,747

DISPLAY STAND

Herbert B. Feist, Ripley, Tenn.

Application July 29, 1947, Serial No. 140,587

Term of patent 3½ years

(Cl. D80—9)

To all whom it may concern:

Be it known that I, Herbert B. Feist, a citizen of the United States, residing at Ripley, county of Lauderdale, and State of Tennessee, have invented a new, original, and ornamental Design for a Display Stand, of which the following is a specification, reference being had to the accompanying drawing, forming a part thereof.

I claim:

The ornamental design for a display stand, as shown.

HERBERT B. FEIST.
